United States Patent Office

Des. 224,366
Patented July 18, 1972

224,366

BREAD TRAY

Houston Rehrig, Pasadena, Calif.
(4291 Bandini Blvd., Los Angeles, Calif. 90023)

Filed Oct. 27, 1970, Ser. No. 25,683

Term of patent 14 years

Int. Cl. D3—02

U.S. Cl. D87—1

FIG2

FIG 3

FIG 4

FIG 5

FIG.6

FIG.7

FIG.8

FIG.9

FIG.10

FIG.11

FIG. 1 is a perspective view of a bread tray showing my new design;

FIG. 2 is a top plan view thereof;

FIG. 3 is a side elevation view thereof;

FIG. 4 is an end elevation view thereof;

FIG. 5 is a fragmentary bottom plan view thereof;

FIG. 6 is a fragmentary sectional view thereof taken on line 6—6 of FIG. 2;

FIG. 7 is a fragmentary sectional view thereof taken on line 7—7 of FIG. 2;

FIG. 8 is a fragmentary sectional view thereof taken on line 8—8 of FIG. 2;

FIG. 9 is a fragmentary sectional view thereof taken on line 9—9 of FIG. 2;

FIG. 10 is a fragmentary sectional view thereof taken on line 10—10 of FIG. 2; and

FIG. 11 is a fragmentary sectional view thereof taken on line 11—11 of FIG. 2.

I claim:

The ornamental design for a bread tray, substantially as shown.
